SLIDE HOLDER

Jon Wilm, Sacramento, Calif.
(4557 Aldrich Road, Bellingham, Wash. 98225)

Filed Mar. 14, 1973, Ser. No. 341,082

Term of patent 14 years

Int. Cl. D16—99

U.S. Cl. D61—15

FIG. 1.

FIG. 2.

FIG. 5.

FIG. 3.

FIG. 4.

FIG. 1 is a front, top and right side perspective view of a slide holder showing my new design with the cover removed;

FIG. 2 is an exploded front, bottom and right side perspective view of the slide holder and cover therefor;

FIG. 3 is an exploded front elevational view thereof;

FIG. 4 is an exploded side elevational view thereof; and

FIG. 5 is a front, top and right side perspective view of the slide holder in covered condition.

I claim:

The ornamental design for a slide holder, substantially as shown and described.
